UNITED STATES PATENT OFFICE.

FRED T. ZACHER, OF ST. LOUIS, MISSOURI.

FOLDING MACHINE.

Application filed June 28, 1924. Serial No. 722,975.

To all whom it may concern:

Be it known that I, FRED T. ZACHER, a citizen of the United States, residing at St. Louis, Missouri, have invented a new and useful Folding Machine, of which the following is a specification.

This invention relates to improvements in folding machines.

The invention comprises mechanism for use in a sheet feeding and folding machine whereby, when a sheet is folded to form page leaves, the leaves are secured together along the fold lines as an incident to the operation of the folding mechanism.

Another object of the invention is to provide mechanism of the character and for the purpose stated in the preceding paragraph, in combination with mechanism for cutting the leaves at their end folds to permit separation of the leaves while said leaves remain adhesively united along their median folded line.

Another object of the invention is to provide mechanism for discharging from the machine the strips cut from the folded sheet so that said strips will not become mixed with the finished product.

Other objects will appear from the following description, reference being made to the drawing in which—

Fig. 1 is a plan view of a part of a well known sheet feeding and folding machine which I have selected for the purpose of illustrating the embodiment of the present invention.

Fig. 2 is a sectional view on the line 2—2 of Fig. 1.

The sheet feeding and folding machine in which the present invention is shown is known as the Cleveland folder, the sheet feeding mechanism of which is in substantial conformity with the disclosure of Trautman Patent No. 1,413,245, dated April 18, 1922, and the folding mechanism of which is substantially disclosed in Olson Patent No. 1,390,213, dated September 6, 1921. As disclosed in said patents the feeding rollers *b* and *b'* move the sheets from the supporting table *c* to the delivery table comprising angularly positioned horizontal rolls *d*. The feeding rollers *b* and *b'* operate upon the sheets in the well known manner; the upper and larger roller *b* engaging and individually advancing the topmost sheet to the rolls *d*, while the lower roller *b'* acts upon the edges of the adjacent sheets to retard their

advance and insure their individual feeding. Both of the rollers *b* and *b'* are operated in a counterclockwise direction as seen in Fig. 2. The rolls *d* are actuated by the belt *d'* to move the sheets individually toward the folding mechanism. From the rolls *d* the sheets pass between the buckling rolls *e* and *f* and thence to the folding mechanism including a roll *g* cooperating with the roll *f*. As is well known machines of the type illustrated are operable to fold a sheet longitudinally and transversely to provide a plurality of page leaves. Certain of the page leaves are united at their folded ends which makes it necessary to cut said folded ends to permit opening or separation of the leaves.

My invention comprises mechanism embodied in a folding machine for adhesively uniting the page leaves of pamphlets along their median fold lines and for cutting the folded ends of the page leaves to permit separation thereof. As shown a shaft 1 is supported in advance of the folding mechanism in bearings 2 and is rotated by a belt 3 engaging a pulley 4 on the shaft 5 of the roller *b* and a pulley 6 on the shaft 1. A disc 7 is attached to the shaft 1 and contacts with the sheets as they are fed to the folding mechanism by the rolls *d*. The speed of rotation of the disc 7 is the same as the speed of movement of the sheets, so that the disc 7 neither retards nor accelerates the movement of the sheets passing to the folding mechanism of the machine. Preferably a number of notches 8 are formed in the periphery of the disc 7 to receive and apply to the sheet passing under the disc a sufficient quantity of paste to secure the sheet together along the fold line of the leaves forming the pamphlet. A paste receptacle 9 has arms 10 engaging the shaft 1 and is supported in proper relationship to the disc 7 by a connection 11 extending to some stationary part of the machine. A slotted discharge chute 12 extends from the bottom of the receptacle 9 toward the disc 7 and receives the disc 7 in the slot in the end of said chute. As the disc 7 rotates a part of the paste in the receptacle 9 adheres to the periphery of said disc and enters the notches 8 and as the disc rotates the paste is deposited in a straight line upon the sheet passing to the folding mechanism.

The roll *e* is formed with a number of spaced circumferential grooves 13 which permit the sheets to pass said roll without the

line of paste making contact with the roll. The disc 7 may be placed in any one of various selected adjustments on the shaft 1 as required by the width of the sheets being folded. In any of its adjusted positions the disc 7 is in line with one of the grooves 13.

I am aware that the invention may be varied and that it may be applied to different types of folding machines.

10 I do not restrict myself unessentially in these or other particulars, but what I claim and desire to secure by Letters Patent is:—

15 1. In a machine of the character described, the combination with a lower and an upper buckling roll, the latter of which has a circumferential groove, and devices for feeding sheets between said rolls, of a disc supported above said devices in line with said groove, a receptacle, means for conducting adhesive material from said receptacle to the periphery of said disc, and means for rotating said disc and thereby applying a line of said adhesive material to the sheets in line with said groove.

20 25 2. In a machine of the character described, the combination with a lower and an upper buckling roll, the latter of which has a number of circumferential grooves, of

a shaft, a disc adjustable on said shaft in line with any selected one of said grooves, 30 means for applying adhesive material to the periphery of said disc, means for rotating said shaft and said disc, and means for feeding sheets of paper toward said rolls and into contact with said disc whereby a line of adhesive material is applied to each sheet of paper in line with the groove with which said disc alines.

3. In a machine of the character described, the combination of a lower and an upper buckling roll, the latter of which has a number of circumferential grooves, a shaft supported parallel with said rolls, a disc adjustable on said shaft in line with any one of said grooves, a receptacle pivotally supported by said shaft, means for conducting adhesive material from said shaft to the periphery of said disc, devices for feeding sheets of paper between said rolls, and means for rotating said disc into contact with the paper passing to said rolls and thereby applying a line of adhesive material to the paper in line with the groove with which said disc alines.

FRED T. ZACHER.
